CLAIM

The ornamental design for a battery charger for an elongated battery, as shown and described.

DESCRIPTION

FIG. 1 is a perspective view of a battery charger for an elongated battery showing my new design. The broken line showing of the battery and the accompanying lead lines are included for the purpose of illustrating environmental elements only and form no part of the claimed design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

FIG.1

FIG.3

FIG.2

FIG. 4
